UNITED STATES PATENT OFFICE.

EDWARD M. WAGNER, OF DENVER, COLORADO.

BURGLAR-ALARM LOCK.

SPECIFICATION forming part of Letters Patent No. 632,664, dated September 5, 1899.

Application filed February 6, 1899. Serial No. 704,708. (No model.)

To all whom it may concern:

Be it known that I, EDWARD M. WAGNER, a citizen of the United States of America, residing at Denver, in the county of Arapahoe and State of Colorado, have invented certain new and useful Improvements in Burglar-Alarm Locks; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to a burglar-alarm lock, my object being to provide a combined door-lock and burglar-alarm so arranged that the turning of the knob-spindle sets off the alarm. The spindle passes through the gong or bell, which may be mounted in any suitable manner. The normally-locked spring-actuated mechanism for operating the hammer or clapper is released by turning the spindle.

25 I do not limit the invention to any specific construction of mechanism for operating the bell hammer or clapper. The mechanism illustrated in the drawings and herein described is similar to that used in alarm-clocks and will answer every purpose, though any other suitable mechanism may be employed.

In the drawings, Figure 1 shows a lock equipped with my improvements, one side of the case being removed. Fig. 2 illustrates the lock viewed from the opposite side. Fig. 3 is a vertical section taken through the escutcheon-plates on a plane parallel with the spindle. In this view one end of the lock-casing is removed, the parts within being shown in elevation. Fig. 4 is a detail view of the latch-bolt. Fig. 5 is a face view of the escutcheon-plate employed in connection with the key for winding the alarm mechanism. 35 In this view the winding-key is shown in section and a vertically-sliding locking device in elevation. Fig. 6 is a detail view of the locking device. Fig. 7 is a detail view of the sliding plate for locking the alarm mechanism against movement. This plate is shown in connection with toggle members for operating it. Fig. 8 is a side view of the lock,

showing the relative position of the escutcheon-plates. Fig. 9 is a fragmentary view of the inner escutcheon-plate with the knob removed. This view shows the sound-openings. Fig. 10 illustrates the swivel-joint connection between the two spindle parts.

Similar reference characters indicating corresponding parts in the views, let the numeral 5 designate a square two-part spindle. These parts are connected together in the center by a swivel-joint or otherwise, whereby each part is allowed to move independently of the other part. Upon each spindle part is mounted a cam 6 for operating the latch-bolt 7. The outer cam is pivotally connected with a link 8, forming, with another link 9, a toggle-joint. These toggle links or members are connected with each other by a pin 10. The link 8 is connected with the cam by a screw-pin 12, while the link 9 is connected with the locking-plate 13 by a screw-pin 14. The plate 13 slides between guide-lugs 15, attached to the lock-casing. Its free extremity is forked or bifurcated (see Fig. 7) to straddle the spur-wheel 16. One arm of the fork is adapted to engage a recess 16^a formed in the edge of the wheel 16 adjacent the teeth, the thickness of this wheel being increased, as shown at 16^c, 40 for the purpose. This plate 13 is normally held in the locked position—that is to say, in engagement with the recess 16^a of the wheel 16—by a leaf-spring 17. The wheel 16, whose periphery is provided with pins or sprockets, is loosely mounted on a shaft 18, journaled in the casing-plates. A coil-spring 19 is attached to this shaft at one extremity, its opposite extremity being secured or anchored to a pin 20 made fast to the lock-casing. This 45 spring is coiled around the shaft adjacent the wheel 16 on one side. On the opposite side of the wheel 16 is located a ratchet-wheel 21, whose teeth are engaged by a dog 22, pivotally mounted on the wheel 16, and held in operative position by a spring 23, also mounted on the wheel 16. The coil-spring 19 is wound or tightened by applying a key 24 to the shaft 18 and turning the shaft in the direction indicated by the arrows in Figs. 1 and 2. The dog 22, co-operating with the ratchet-wheel, locks the spring against recoil as long as the spur-wheel 16 is locked by the key-plate 13. The teeth of the spur-wheel 16 engage the

pins or bars 25^a of a lantern-wheel 25, mounted on a shaft 25^b, to which is attached a toothed escapement-wheel 26, engaged by a pallet 27, to which is attached one extremity 5 of an arm 28, whose opposite extremity is provided with a threaded opening 28^a, into which may be screwed from either side a hammer or clapper 29, which projects through a slot 30, formed in one side of the casing. This 10 hammer is located in suitable proximity to the bell or gong 31, which, as shown in the drawings, is mounted on the spindle 5. It may, however, be supported in any other suitable manner. This gong is located between 15 the lock-case 32 and the escutcheon-plate 33, which is provided with openings 33^a, surrounding the spindle just outside the bell 31, whereby the sound of the hammer on the gong may be easily heard.

20 The operation of the mechanism is as follows: As the outer knob 34, or that remote from the gong, is turned the spindle 5 and the cam 6 are actuated sufficiently to withdraw the plate 13 from the spur-wheel 16 through the instrumentality of the toggle-joint members 8 and 9. As soon as this occurs the recoil of the spring 19, acting on the wheel 16, rotates the latter, which operates the lantern-wheel 25, the toothed escapement-wheel 26, and the pallet 27, which imparts an oscillating movement to the hammer-arm 28, causing the hammer to strike the gong and sound the alarm. After the plate 13 has been withdrawn from engagement with the 35 wheel 16 the latter will make one complete revolution before the locking-plate can return to the locking-recess 16^a of the wheel. One revolution of this wheel 16 will operate the alarm mechanism sufficiently for all practical purposes.

If it is not desired to operate the alarm mechanism when the knob 34 is turned, the said mechanism may be locked against operation through the instrumentality of the key 45 24, which is provided with grooves 24^a, adapted to receive one extremity of a sliding dog 35, mounted on a small escutcheon-plate 36, whose relative position is illustrated in Fig. 8. Behind the dog 35 is located a spring 37, 50 which retains the dog in the raised or unlocked position until moved downwardly. The plate 36 is provided with guides 38, which hold the dog in operative relation with the plate. The dog 35 is provided with a 55 stop 35^a. It is evident that when the dog 35 engages the key 24 the latter as well as the shaft 18, the parts mounted thereon, and the other elements of the alarm mechanism will be locked against movement independently 60 of the locking-plate 13. The keeper ends of the shaft 18 are threaded, as shown at 18^a, to receive the key 24, which may be screwed thereon and detached therefrom at will.

The toggle-joint-operated plate 13 may, if 65 desired, be actuated from the key-operated plate 39. In this event the toggle-link 8 will be connected with the bolt at a point 40 and

the plate would move between the guide-lugs 15^a attached to the lock-casing. The bolt 39 is cut away, as shown at 39^a, to allow the toggle-joint to operate. It is evident that the locking-plate 13 would then act on the spur-wheel 16 in the same manner as when connected with the cam on the spindle, as heretofore explained. The locking-plate 13 is reversible, being provided with two arms 13^a, either of which will engage and lock the spur-wheel against rotation. This locking-plate is provided with an opening 13^c to receive the extremity of the spring 17. The position of the 80 bell-hammer may also be reversed to permit the attachment of the bell or gong to either spindle part at pleasure.

It will be observed that both lugs 6 are apertured to receive the screw-pin 12, whereby the toggle connection for actuating the locking-plate 13 may be applied to either lug indifferently; also, that both sides of the casing 32 are provided with a slot 30, through which the hammer-arm 29 projects. By reason of these features the lock becomes reversible.

Having thus described my invention, what I claim is—

1. In an alarm-lock, the combination with 95 the knob-spindle, of a bell or gong mounted on the spindle, a hammer, and suitable mechanism for actuating the hammer, said mechanism being arranged to be set off or actuated by the movement of the spindle.

2. In a combined door-lock and burglar-alarm, the combination with a casing and knob-spindle, of a bell or gong mounted on the spindle outside of the casing, a hammer, and hammer-actuating mechanism inclosed 105 by the casing, which is slotted to allow the hammer to protrude to engage the bell, the hammer-actuating mechanism being arranged to be set off by a moving part of the lock.

3. The combination with the lock mechanism, of alarm mechanism comprising a spur-wheel, a coil-spring, a ratchet and dog for winding the spring, a lantern-wheel, a toothed escapement-wheel, a pallet, a hammer connected with the pallet, a gong or bell located in proximity to the hammer, and a spring-held sliding device normally engaging and locking the spur-wheel against movement, said locking device being connected with a moving 115 part of the lock whereby the operation of the latter actuates the locking device and releases the alarm mechanism.

4. The combination with a lock mechanism, lock-casing and a knob-spindle, of a bell or gong mounted on the spindle, a hammer located in proximity to the bell, normally-locked, spring-actuated mechanism for operating the hammer, said mechanism being located entirely within the lock-casing, and a 125 suitable connection between said mechanism and a part of the lock, whereby the movement of the lock part releases the hammer-actuating mechanism.

5. The combination with the knob-spindle, of a bell or gong mounted thereon, a hammer located in suitable proximity to the gong, and normally-locked spring-actuated mechanism 5 for operating the hammer, said mechanism being connected with a moving part of the lock whereby, as the latter is operated the hammer-operating mechanism is released.

6. In a combined lock and burglar-alarm, 10 the combination with the lock mechanism, and casing inclosing said mechanism, and a knob-spindle, of a bell or gong mounted on the spindle, a bell-hammer, hammer-actuating mechanism, arranged to be set off by a 15 moving part of the lock, and an escutcheon-plate located adjacent the bell or gong and provided with openings that facilitate the escape of the alarm sound.

7. The combination with the knob-spindle 20 and the latch-operating cam, of a bell or gong mounted on the spindle, a vibrating hammer located in proximity to the bell, spring-actuated mechanism for operating the hammer, a device for locking said mechanism against 25 movement, and a toggle-joint connection between said device and the cam on the spindle whereby the movement of the spindle actu-

ates the said device and releases the hammer-actuating mechanism.

8. In a combined lock and burglar-alarm, 30 the combination with the knob-spindle and the latch-bolt-operating cam, of a bell or gong mounted on the spindle, a vibrating hammer located in proximity to the bell, a shaft journaled in the lock-casing, a spur-wheel loose 35 on the shaft, a ratchet-wheel fast on the shaft, a locking-pawl mounted on the spur-wheel and engaging the ratchet-wheel, a lantern-wheel connected with the spur-wheel, a toothed escapement-wheel operated by the lantern-wheel, a pallet engaging the escapement-wheel and connected with the hammer, a device engaging the spur-wheel and locking it against movement, and a toggle connection between 40 said device and the latch-operating cam 45 whereby the movement of the spindle releases the hammer-operating mechanism.

In testimony whereof I affix my signature in presence of two witnesses.

EDWARD M. WAGNER.
